ATTORNEY

UNITED STATES PATENT OFFICE.

RICHARD BROWN, OF ALLIANCE, OHIO.

FOUNDRY-LADLE GEAR.

SPECIFICATION forming part of Letters Patent No. 289,499, dated December 4, 1883.

Application filed August 11, 1883. (No model.)

To all whom it may concern.

Be it known that I, RICHARD BROWN, a citizen of the United States, residing at Alliance, county of Stark, and State of Ohio, have invented certain new and useful Improvements in Foundry-Ladle Gears; and I do hereby declare the following to be a description of the same, and of the manner of constructing and using the invention, in such full, clear, concise, and exact terms as to enable any person skilled in the art to which it appertains to construct and use the same, reference being had to the accompanying drawings, which form a part of the specification.

15 Figure 1 is a front view of the ladle and gear. Fig. 2 is a side elevation of same. Fig. 3 is a detail plan. Fig. 4 is a detail view, showing in longitudinal vertical section the connecting extremities of the hand-wheel shaft and bevel-wheel shaft.

20 A is the ladle. B and B² are the hangers, and C the yoke that unites them at their top extremities. These in combination compose the sustaining frame-work of the ladle and its attachments.

25 D is the neck of the yoke, and d is its eye, into which hooks the chain from the swinging crane. The upper portions, b, of the hangers B and B² are cylindrical. The lower portions, b', are square, for the better securing of the frame-bracket I².

30 E is a broad-band axle encircling the ladle, and securely clamped to it by clamps and bolts e. The extremities of this axle-band unite on each opposite side of the ladle, where they are rounded into trunnions E² and E³. These trunnions are journaled into boxes F and F², provided for them in the bossed bearings e' at the lower extremities of the hangers

35 B and B². This axle-band is located about midway from the top to the bottom of the ladle. The trunnion E² passes entirely through the journal-box F, and is rigid with the worm-wheel G. This worm-wheel G is rotated by the worm H, which is rigid on the shaft I, located above said worm-wheel. This worm-shaft I has its bearings in the bracket I², which is provided with an arm, I³, having a sleeve, I⁴, that receives and sustains the driving-shaft

40 J. The front end of the worm-shaft I has rig-

idly secured to it the bevel-wheel K, which meshes in with the smaller bevel-wheel K². This latter bevel-wheel is rigid on the inner end of the driving-shaft J. The shaft J works in the sleeve I⁴. The bracket I² is firmly secured to the hanger B², above the axle, by bolts b². The driving-shaft J has a collar, j, forged on it, adapted to hold it more steady, said collar being fitted between sleeve I⁴ and shaft J².

45 J² is a hand-shaft provided with the fixed hand-wheel M. By this hand-wheel, with its connected mechanism, as described, the ladle is upset. The inner end of this hand-shaft is bossed and tubular, adapted to fit over and onto the outer end of the driving-shaft J, where it is locked by a cotter, N, passing through suitable slots, n. By the removal of the cotter the hand-shaft, with its wheel, can be removed out of the way when desired.

50 The described upsetting-gear can be affixed to either side of the ladle, and the adaptation of its parts is such as to cause the operator to stand on the side of the ladle in clear and unobstructed view of the discharging-spout, thus enabling him fully to oversee his work.

55 What I claim is—

1. In a ladle-gear adapted to be suspended from a crane, the combination, with hangers B B², trunnion E², journaled in its lower extremity, and bracket I², projecting outwardly from said hanger, of worm-wheel G, mounted on said trunnion, worm-shaft I, mounted in the main body of the bracket, and driving-shaft J, mounted in sleeve I⁴, formed on arm I³ of said bracket, substantially as set forth.

2. In a ladle-gear adapted to be suspended from a crane, the combination, with trunnion E², journaled in the lower extremity of hangers B B², and bracket I², projecting outwardly from said hanger above journal-box F, of worm-wheel G, rigid on said trunnion, worm-shaft I, located above the worm-wheel and mounted in the main body of the bracket, and driving-shaft J, mounted in sleeve I⁴, formed on said arm I³ of the bracket, substantially as set forth.

3. In a ladle-gear, the combination, with hangers B B², bracket I², provided with arm I³, having sleeve I⁴ and worm-wheel G, of worm-

shaft I, driving-shaft J, having collar j , and hand-shaft J^2 , substantially as set forth.

4. In a ladle-gear, the combination, with hangers B B², bracket I², formed with arm I³, having sleeve I⁴, and worm-shaft I, of driving-shaft J, having collar j , hand-shaft J^2 , formed with a tubular end fitting on the driving-shaft, and cotter N, locking in slots n , substantially as set forth.

In testimony that I claim the foregoing to be my invention I have hereunto set my hand this 3d day of August, A. D. 1883.

RICHARD BROWN.
